US0D1008280S

(12) **United States Design Patent** (10) **Patent No.:** **US D1,008,280 S**
(45) **Date of Patent:** **** Dec. 19, 2023**

(54) **DISPLAY SCREEN OR PORTION THEREOF WITH A GRAPHICAL USER INTERFACE WITH ICONS**

(71) Applicant: **DexCom, Inc.**, San Diego, CA (US)

(72) Inventors: **Michael Robert Mensinger**, San Diego, CA (US); **Eric Cohen**, San Diego, CA (US); **Phil Mayou**, San Diego, CA (US); **Eli Reihman**, San Diego, CA (US); **Katherine Yerre Koehler**, San Diego, CA (US); **Rian Draeger**, San Diego, CA (US); **Angela Marie Traven**, San Marcos, CA (US)

(73) Assignee: **Dexcom, Inc.**, San Diego, CA (US)

(**) Term: **15 Years**

(21) Appl. No.: **29/717,299**

(22) Filed: **Dec. 16, 2019**

Related U.S. Application Data

(60) Continuation of application No. 29/667,075, filed on Oct. 18, 2018, now Pat. No. Des. 870,144, which is a continuation of application No. 29/603,648, filed on May 11, 2017, now Pat. No. Des. 835,146, which is a division of application No. 29/577,019, filed on Sep. 8, 2016, now Pat. No. Des. 789,968, which is a division of application No. 29/495,687, filed on Jul. 2, 2014, now Pat. No. Des. 767,605, which is a continuation-in-part of application No. 13/842,679, filed on Mar. 15, 2013, now Pat. No. 9,801,541.

CLAIM

The ornamental design for a display screen or portion thereof with a graphical user interface with icons, as shown and described.

DESCRIPTION

FIG. 1 shows a front view of a first embodiment of the display screen or portion thereof with the graphical user interface with icons showing our new claimed design; and, FIG. 2 shows a front view of a second embodiment thereof. The peripheral broken lines illustrate a display screen or portion thereof, which form no part of the claimed design. The interior broken lines illustrate portions of the graphical user interface with icons that form no part of the claimed design.
